PUFF IRON

George W. Wardwell, Jr., Nichols, Conn., assignor
to General Electric Company, a corporation of
New York

Application August 23, 1934, Serial No. 741,091

8 Claims. (Cl. 68—9)

My invention relates to puff irons for ironing presses of the type having two cooperating pressing members which are brought into pressing engagement to iron work placed between the pressing members.

In ironing presses of this type there are certain types of irregular work such as ruffles and the like which are not conveniently ironed by placing between the pressing members. Work of this type is more readily ironed by drawing the work across a heated surface of small dimensions which is called a puff iron.

An object of my invention is to provide an ironing machine having an improved puff iron which is carried within the edges of one of the pressing members when not in use and which is extended to a position projecting beyond the pressing member when in use.

Further objects and advantages of my invention will become apparent as the following description proceeds.

In the accompanying drawing, Fig. 1 is a plan view of a heated shoe for an ironing press having a puff iron embodying my invention; Fig. 2 is a sectional view taken on line 2—2 of Fig. 1; and Fig. 3 is a sectional view taken on line 3—3 of Fig. 1.

Referring to the drawing, I have illustrated my invention in connection with a heated shoe 1 which forms one of the pressing members of an ironing press and may be supported in any suitable manner. The shoe is preferably made of metal such as aluminum and is heated by an electric heating element 3 clamped within a groove 4 formed in a rib in the upper surface of the shoe by clamps 5, any suitable number of which may be used. The shoe is provided with a metal cover 6 which fits against the outer edge of a rib 20 extending around the edge of the shoe and is spaced from the upper surface of the shoe.

In accordance with my invention, I have provided a puff iron 7 which is slidably carried on the upper surface of the shoe beneath the cover 6. The puff iron is made from a bar of metal 45 and has a working surface 8 at the front end which is spaced from the upper surface of the shoe and has a part to the rear of the working surface which is slidable in a groove 9 in contact with the upper surface of the shoe. When the puff iron is not in use, the iron is carried within the edges of the shoe as illustrated in Fig. 2. The working surface 8 of the puff iron is provided with rounded corners in order to provide a smooth surface across which the work to be ironed may be drawn. The part of the puff iron

to the rear of the surface 8 is maintained in contact with the upper surface of the shoe by a spring 10 which is supported from the shoe by a bracket 11 attached to a boss 11a. Projections 12 and 13 are provided on the upper surface of the puff iron to the rear of the working surface and are engaged by the spring when the puff iron is in the retracted and extended positions respectively. These projections increase the pressure tending to hold the puff iron in contact with the heated shoe. When the puff iron is between the extended and the retracted positions, the spring engages the portion 14 of the iron between the projections 12 and 13 and, since this portion is further from the bracket 11, the spring exerts less pressure on the puff iron, and the puff iron may be more readily moved. A slot 21 is provided in the cover through which the puff iron may be extended.

For sliding the puff iron into and out of the shoe, I have provided a handle 15 which is pivotally connected to the puff iron at the rear of the working surface by a pin 17 which lies within an elongated slot 16 formed in the handle. The lower end of the pin lies within a recess in the under side of the puff iron and a spring 17a arranged between a washer 17b, and the puff iron forces the head of the pin against the upper surface of the handle and holds the handle against the upper surface of the iron. The washer 17b is held on the pin by a bead formed on the end of the pin. The front end of the handle extends beyond the tip of the iron and is provided with an enlarged portion 22 of insulating material which may be gripped by the operator. When the puff iron is pushed within the shoe, the elongated slot 16 permits the rear end of the handle to slide between projections 18 on the upper surface of the puff iron which maintain the handle in alignment with the iron. When the puff iron is pulled out of the shoe, the rear end of the handle is pulled from between the projections 18 and, when the puff iron reaches the extended position, which is shown by dotted lines in Fig. 1, the handle may be swung away from the working surface by pivoting on the pin 17. A shoulder 19 on the lower surface of the puff iron engages the inner surface of the rib 20 at the front edge of the shoe and limits the outward movement of the puff iron. Inward movement of the iron is limited by the engagement of the rear end of the iron with the rib 20 at the rear of the shoe.

When the puff iron is not in use, it is retained within the edges of the shoe and is maintained in thermal contact with the heated part of the

shoe by the spring 10 which engages the projection 12. When the puff iron is in use, the working surface 8 of the iron is extended beyond the edge of the shoe and the inner part of the iron is maintained in thermal contact with the heated part of the shoe by the spring 10 which then engages the projection 13. By this arrangement, the puff iron is maintained in a heated condition so that it is ready for use whenever the shoe is heated. When the puff iron is not in use, it is kept out of the way in the space between the cover and the shoe so that it does not interfere with the normal operation of the ironing press.

Although I have shown the puff iron embodying my invention in connection with a particular type of pressing member, it may be applied to other pressing members, and I intend in the appended claims to cover all modifications which do not depart from the spirit and scope of my invention.

What I claim as new and desire to secure by Letters Patent of the United States is:

1. In an ironing press having a heated shoe, a puff iron carried within the edges of said shoe and having a working surface movable to a position projecting beyond an edge of said shoe when in use and having a part to the rear of said working surface remaining within the edges of said shoe, and means including a spring for maintaining the part of said iron within said shoe in contact with said shoe to heat said working surface.

2. In an ironing press having a heated shoe, a puff iron carried within the edges of said shoe and having a working surface movable to a position projecting beyond an edge of said shoe when in use, and a handle pivotally connected to said iron at the rear of said working surface and projecting beyond the tip of said iron for sliding said iron into and out of said shoe, said pivotal connection permitting said handle to be swung away from the working surface when the iron is in use.

3. In an ironing press having a heated shoe, a puff iron carried within the edges of said shoe and having a working surface movable to a position projecting beyond an edge of said shoe when in use and having a part to the rear of said working surface remaining within the edges of said shoe, a spring engaging said rear part for forcing the rear part of the puff iron into contact with the shoe, said part having a pair of spaced projections thereon, one of which is engaged by said spring when the iron is in the extended position and the other of which is engaged by said spring when the iron is in the retracted position whereby the pressure exerted by the spring on the iron is increased when the iron is in the extended and the retracted positions.

4. In an ironing press having a heated shoe, a cover for said shoe spaced from the upper surface of said shoe, a puff iron carried within the edges of said shoe between the upper surface of said shoe and said cover and having a working surface movable to a position projecting beyond an edge of said shoe when in use and having a part to the rear of said working surface remaining within the edges of said shoe, and means including a spring for maintaining the part of said iron within said shoe in contact with said shoe to heat said working surface.

5. In an ironing press having a heated shoe, a puff iron carried within the edges of said shoe and having a working surface movable to a position projecting beyond an edge of said shoe when in use, a handle pivotally connected to said iron at the rear of said working surface for sliding said iron into and out of said shoe, said pivotal connection permitting said handle to be swung away from said working surface when the iron is in use, and means for preventing pivoting of said handle when the iron is being moved within the shoe.

6. In an ironing press having a heated shoe, a puff iron carried within the edges of said shoe and having a working surface movable to a position projecting beyond an edge of said shoe when in use and having a part to the rear of said working surface remaining within the edges of said shoe, means for pressing the rear part of the iron against said shoe, and means for decreasing the pressure on the iron when the iron is between the extended and the retracted positions.

7. In an ironing press having a heated shoe, a puff iron carried within the edges of said shoe and having a working surface movable to a position projecting beyond an edge of said shoe when in use and having a part to the rear of said working surface remaining within the edges of said shoe, and spring means engaging the rear part of the iron for pressing the rear part of the iron against said shoe, said iron having a depressed portion within which said spring means fits when the iron is between the extended and the retracted positions whereby the pressure exerted on the iron is decreased.

8. In an ironing press having a heated shoe, a puff iron carried within the edges of the shoe and having a working surface movable to a position projecting beyond an edge of said shoe when in use and having a part to the rear of said working surface remaining within the edges of the shoe, and means for maintaining the part of said iron within said shoe in contact with said shoe to heat said working surface.
